(Cl. D81—10)

To all whom it may concern:

Be it known that we, David M. Trilling and George H. Rich, citizens of the United States, respectively residing at Merion, in the county of Montgomery and State of Pennsylvania, and at Philadelphia, in the county of Philadelphia and State of Pennsylvania, have invented a new, original, and ornamental Design for Space Heater, of which the following is a specification, reference being had to the accompanying drawing, forming a part thereof, wherein the figure is a perspective view of a space heater, showing my new design.

The space heater of the present design is characterized in that it is of cabinet form, as shown, having a perforated top panel and perforated side and end walls, the side and end walls respectively opposite those shown in the drawing being the same in appearance as those shown.

I claim:

The ornamental design for a space heater, as shown and described.

DAVID M. TRILLING.
GEORGE H. RICH.
